(57) **CLAIM**

The ornamental design for the male genital shield, as shown and described.

DESCRIPTION

This application claims priority to an earlier filed U.S. Non-Provisional Application entitled Genital Shield for Reducing the Transmission of Sexually Transmitted Diseases filed on Dec. 9, 2013 having U.S. application Ser. No. 14/100,318.

FIG. 1 is a front elevational view of a male genital shield showing my new design.

FIG. 2 is a right side elevational view of the male genital shield, the left side being a mirror image; and,

FIG. 3 is a rear elevational view of the male genital shield.
